UNITED STATES PATENT OFFICE.

HERMAN T. MENDELSOHN, OF NEW YORK, N. Y., ASSIGNOR TO SIMON & MENDELSOHN,
OF NEW YORK, N. Y., A FIRM.

DESIGN FOR AN ARTICLE OF MANUFACTURE.

56,373.

Specification for Design.

Patented Oct. 5, 1920.

Application filed May 28, 1920. Serial No. 385,072. Term of patent 7 years.

To all whom it may concern:

Be it known that I, HERMAN T. MENDELSOHN, a citizen of the United States, and a resident of the city of New York, borough of Manhattan, county and State of New York, United States of America, have invented a new, original, and ornamental Design for an Article of Manufacture, of which the following is a specification, reference being had to the accompanying drawing, forming part thereof, which shows my design as applied to a textile fabric.

The figure represents a plan view of one repeat of my design as applied to a textile fabric and consists of a specified number of groupings of conventionalized representations of humming birds.

The design is printed, painted, stamped, or otherwise marked, upon textiles or paper.

What I claim and desire to secure by Letters Patent is:

The ornamental design for an article of manufacture as shown and described.

HERMAN T. MENDELSOHN.
